UNITED STATES PATENT OFFICE.

HENRY H. CUTLER, OF CHICAGO, ILLINOIS.

SELF-STARTER FOR ELECTRIC MOTORS.

SPECIFICATION forming part of Letters Patent No. 653,470, dated July 10, 1900.

Application filed June 8, 1899. Serial No. 719,815. (No model.)

To all whom it may concern:

Be it known that I, HENRY H. CUTLER, a citizen of the United States, residing at Chicago, in the county of Cook and State of Illinois, have invented a certain new and useful Improvement in Self-Starters for Electric Motors, of which the following is a full, clear, concise, and exact description, reference being had to the accompanying drawings, forming a part of this specification.

My invention relates to a self-starter for electric motors, my object being to provide means whereby the armature-resistance of the electric motor may be automatically removed from circuit during the starting of the motor.

In accordance with my invention I provide in circuit with the armature of the motor the usual starting-resistance and provide a plurality of electromagnets arranged to be successively operated to in turn remove portions of the starting-resistance from circuit, whereby the armature is permitted to start up gradually and build up in speed until normal operation results. In practice I divide the armature-resistance into sections and provide an electromagnet for controlling each of the several sections, the first electromagnet being arranged to become energized when the counter electromotive force of the armature has reached a certain value, to thereby cut out one of the sections of the resistance and lower the resistance to which the armature-current is subjected, thus permitting the speed of the armature to increase. When the counter electromotive force of the armature has reached a second prearranged value, a second electromagnet is energized to remove another section of the resistance, and so on, the electromagnets being thus successively energized to successively remove the sections of the armature-resistance from circuit until the desired speed has been obtained. The electromagnets are in practice connected in circuit, so that the first electromagnet when energized connects the succeeding electromagnet in circuit. I preferably provide a short circuit about the electromagnet to normally remove the same from operative position, which short circuit when opened includes the electromagnet opera-

tively in circuit. The electromagnets are usually made alike and adjusted to become energized when traversed by a current of a definite value, and by arranging each electromagnet to connect the succeeding electromagnet in series with the same the resistance of the path is increased, thereby cutting down the current, and the succeeding electromagnet remains in circuit unenergized until the rise of voltage brings the current up to the prearranged value.

I have employed the term "electromagnet" as broadly comprehending solenoids and electromagnets, strictly so called.

I have illustrated my invention in the accompanying drawings, in which—

Figure 1 is a plan view of a self-starter embodying my invention. Fig. 2 is a sectional view thereof. Fig. 3 is a diagrammatic view illustrating the arrangements of the circuits. Fig. 4 is a view of a self-starter containing four electromagnets. Fig. 5 is an end view thereof. Fig. 6 is a view illustrating the arrangements of the circuits.

Like characters refer to like parts in the several figures.

The main switch-arm *a*, which controls the circuit of the motor and which is adapted to vibrate between the terminals *a'* *a''*, is shown in the present instance as operated by means of an arm *b*, connected with a float *b'*, whereby the arm is raised when the float descends. A weighted rocking lever *b''* is pivoted at *b'''* upon the pivot of the arm *b* and the switch-arm *a*. The movement of the lever *b''* relatively to the arm *b* is limited by the stops *b⁵* *b⁶*. Upon the pivoted end of the lever *b''* lugs *b⁴* *b⁵* are provided, adapted to engage and move switch-arm *a*. When the arm *b* is raised, the weighted lever *b''* is rocked toward the center of gravity thereof and is shifted beyond the vertical support, when the said lever falls to the left and the lug *b⁴*, engaging the arm *a*, carries the same into engagement with the terminal *a''*, thereby closing the circuit. When the float ascends, the arm *b* is moved downward, thereby throwing the weighted lever *b''* to the right and carrying the switch-arm *a* into engagement with the terminal *a'* to open the motor-circuit.

The main 1 is connected with the terminal

a^2 and the switch-arm a is connected by conductor 3 with the terminal c , between which and the terminal c' the resistance d is connected, while to the terminals $c' c^2$ the resistance d' is connected. The terminal c^2 is connected by conductor 4 with one side of the armature e . The other side of the armature is connected by conductor 5 with the other main 2. The field-coil e' is connected in shunt with the armature. From the terminal c^2 a conductor 6 extends through electromagnet f , thence by conductor 7 to terminal g , which is connected with terminal g' by contact-plate g^2 from the terminal g' . Conductor 8 extends to conductor 5. A terminal g^3 is connected with terminal g' and normally through plate g^4 with terminal g^5 , terminal g^5 being connected by conductor 9 with one end of magnet f' , while the other end of said magnet is connected with the end of magnet f . A conductor 10 extends from conductor 9 through winding f^2 , thence through winding f^3 and conductor 11 to conductor 8. Upon the core f^4 of the solenoid or magnet f is carried a contact-plate f^5 , adapted when the solenoid is raised to bridge together terminals c' and c^2 . Upon the core f^6 of magnet f' contact-plate f^7 is provided, adapted when the core is raised to connect together the terminals c and c' .

In starting the switch-arm a is moved to terminal a^2 and current from main 1 passes through the switch, conductor 3, resistance-coils d and d' , conductor 4 through the armature and to the opposite main 2. Circuit is thus closed through the armature and all of the armature-resistance. The shunt-path for the current around the armature is provided through conductor 6, magnet f , conductor 7, contacts $g g^2 g'$, and conductor 8, and when the counter electromotive force of the armature has been built up to a prearranged value, according to the turns of the windings of the magnet f , said magnet is energized, drawing up core f^4 and moving plate f^5 against terminals $c' c^2$ to short-circuit resistance d' , thereby cutting out a portion of the armature-resistance and permitting the speed of the motor to further increase. The ascent of the core f^4 moves plate g^2 out of engagement with the terminals $g g'$, and the shunt-path around the armature may now be traced over conductor 6, magnet f , magnet f' , conductor 9, contacts $g^5 g^4 g^3$, and conductor 8. When the counter electromotive force of the armature is raised to a second pre-arranged value, magnet f' is energized sufficiently to raise core f^6 , thereby moving plate f^7 into contact with the terminals $c' c$ to short-circuit resistance d and move plate g^4 out of contact with terminals $g^8 g^5$. The magnets $f f'$ are now in shunt with the armature, and as less current than that required to lift the cores in the first instance is sufficient to maintain the cores in their upper position windings $f^2 f^3$ are adapted to be connected in circuit with the windings $f f'$ in this

position to serve as resistances to cut down the current through the magnets, and, furthermore, being in the form of windings they assist in holding the cores in their upper positions. The shunt-circuit may now be traced through conductor 6, windings $f f'$, conductor 10, windings $f^2 f^3$, conductor 11, and conductor 8.

In Figs. 4, 5, and 6 I have illustrated a construction wherein three sections of resistance are provided in the armature. From the main 1 a conductor 12 extends to terminal h , and a conductor 13 extends from conductor 12 through the winding k , thence by conductor 14 through the resistances $k' k^2$, thence by conductor 15 through the contacts $k^3 k^5$ of the controller-switch to the opposite main 2. The end of coil d^2 is connected with terminals c^3, c^4, c^5 , and c^6 , while the opposite end of said coil is connected with terminal c^7 , the end of coil d^3 with terminal c^8 , and the end of coil d^4 with terminal c^9 . Contact-plates $l l' l^2$ are arranged to engage the several terminals, while contact-plate l^3 is arranged to engage the terminals $c^8 h$. The plate l^3 is carried upon the core k^4 of magnet k , which core also carries plate l^4 , adapted to engage terminals $l^5 l^6$. Said core also carries plate m , normally in contact with terminals $m' m^2$. The core o' of magnet o carries plate l and also a plate m^3 , engaging terminals $m^4 m^5$. The core p' of magnet p carries plate l' and also plate m^6 , engaging terminals $m^7 m^8$, and the core r' of magnet r carries plate l^2 and also plate m^9 , engaging terminals $m^{10} m^{11}$, which are connected together by resistance m^{12} . The opposite ends of winding p are connected with terminals $m^4 m^5$, while the opposite ends of winding r are connected with the terminals $m^7 m^8$, and in the normal position these coils are short-circuited. The terminal l^5 is connected by conductor 16 with the brush e' of the armature e , while the other brush e^2 is connected by conductor 17 with the end of resistance-coil d^4 and also with terminal m^{10} .

When the controlling-switch is operated to close together terminals k^3 and k^5 , current flows from main 1 over conductors 12 and 13 through magnet k , conductor 14, resistance k^2 , conductor 15, through the switch to terminal 2. Magnet k is thus energized and attracts core k^1 , thereby moving plate l^3 into engagement with the terminals h and c^3 , and moving plate l^4 into contact with terminals $l^5 l^6$, and moving plate m out of engagement with terminals $m' m^2$. The short circuit about resistance k' is thus opened and resistance k' is inserted in the circuit of magnet k to cut down the current therethrough. Current from main 1 now passes over conductor 12, terminal h , plate l^3 , and terminal c^3 , and thence through the armature-resistance $d^2 d^3 d^4$, conductor 17, and armature e to the opposite main 2. Circuit is thus closed through all of the armature-resistances. After passing through the armature-resistance a portion of

the current passes through contacts $m^{10} m^9$ m^{11} , thence through contacts $m^7 m^6 m^8$, thence by conductor 18 through contacts $m^4 m^3 m^5$ and conductor 19 through magnet o , thence 5 to terminal l^6 , contact-plate l^4 , terminal l^5 , and by conductor 16 to the opposite side of the circuit. The magnet o is thus connected in shunt-circuit with the armature e , and when the counter electromotive force of the 10 armature is built up to a prearranged value magnet o is energized, thereby attracting the core o' and moving plate l into engagement with terminals $c^4 c^7$ to short-circuit resistance d^2 and move plate m^3 out of engagement with 15 contacts $m^4 m^5$, thereby including in the shunt-circuit the winding p . The shunt-circuit around the armature now includes contacts $m^{10} m^9 m^{11}$, contacts $m^7 m^6 m^8$, current then passing through magnet p and magnet o , and 20 thence through contacts $l^6 l^4 l^5$ and conductor 16 to the other side of the line. When the counter electromotive force of the armature builds up to another prearranged value, the magnet p is energized, attracting the core p' 25 and moving plate l' into contact with terminals $c^5 c^8$ and moving plate m^6 out of contact with terminals $m^7 m^8$. The second resistance d^3 is thus short-circuited and removed from the armature-circuit, and the short circuit 30 around the coil r is opened, so that the shunt-circuit around the armature now includes contacts $m^{10} m^9 m^{11}$, magnet r , magnet p , and magnet o , the current then passing through contacts $l^6 l^4 l^5$ and conductor 16 to the opposite side of the circuit. When the counter 35 electromotive force of the armature has built up to a third prearranged value, magnet r is energized, thereby attracting core r' and moving plate l^2 into contact with terminals c^6 40 c^9 and moving plate m^9 out of contact with terminals $m^{10} m^{11}$. The shunt around the armature now includes contact m^{10} , resistance m^{12} , contact m^{11} , and magnets r , p , and o , and the placing of the three magnets in series and 45 the inclusion of the resistance m^{12} in circuit therewith cuts down the current to a value just sufficient to maintain the cores in the elevated position.

Having described my invention, what I 50 claim as new, and desire to secure by Letters Patent, is—

1. In combination an electric motor and a resistance therefor, in series with the armature, a plurality of electromagnets adapted to 55 be successively energized to remove the resistance from circuit step by step, and means controlled by an electromagnet first to operate for operatively including a succeeding

electromagnet in circuit, substantially as described.

60

2. In combination, an electric motor and a resistance therefor, two or more electromagnets adapted to be successively energized to remove the resistance from circuit step by step, a short circuit around one of said electromagnets, and means controlled by the other electromagnet for opening said short circuit to include said short-circuited electromagnet operatively in circuit, substantially as described.

70

3. In combination, an electric motor and a resistance therefor, an electromagnet adapted to be included in a parallel branch around the armature a second electromagnet, and means operated by said first electromagnet 75 for including said second electromagnet in a parallel branch around the armature, substantially as described.

75

4. In combination, an electric motor and a resistance therefor, an electromagnet adapted 80 to be included in a parallel branch around the armature, a second electromagnet, and means operated by said first electromagnet for including said second electromagnet in a parallel branch around the armature, in series with said first electromagnet in said parallel branch, substantially as described.

85

5. In combination, an electric motor and a resistance therefor, an electromagnet in a branch of definite resistance in parallel with the armature, a second electromagnet, and 90 means operated by the first electromagnet for including the second electromagnet in parallel with the armature in a branch of greater resistance, substantially as described.

90

6. In combination, an electric motor and a 95 resistance therefor, a plurality of electromagnets adapted to be connected in parallel with the armature, and means operated by the respective electromagnets for including the succeeding electromagnet in a parallel path 100 of increased resistance, substantially as described.

100

7. In combination, an electric motor and a resistance therefor, a plurality of electromagnets adjusted to be energized by the flow of 105 a current of definite value, and means operated by the electromagnets for including the same in parallel paths of successively increased resistance, substantially as described.

105

In witness whereof I have hereunto 110 subscribed my name in the presence of two witnesses.

HENRY H. CUTLER.
